US00D940304S

(12) **United States Design Patent** (10) **Patent No.:** **US D940,304 S**
(45) **Date of Patent:** **** Jan. 4, 2022**

(54) **RECLOSEABLE SWAB APPLICATOR**

(71) Applicants: **Sonic Packaging Industries, Inc.**,
Westwood, NJ (US); **Nantech Plastics, Inc.**, Ronkonkoma, NY (US)

(72) Inventors: **Howard Thau**, Woodcliff Lake, NJ (US); **Thomas Nagler**, Greenlawn, NY (US); **Michael A Botta**, Ridge, NY (US); **Mian S Yousuf**, Bay Shore, NY (US)

(**) Term: **15 Years**

(21) Appl. No.: **29/728,973**

(22) Filed: **Mar. 23, 2020**

(51) LOC (13) Cl. **24-02**

(52) U.S. Cl.

(57) **CLAIM**

The ornamental design for a recloseable swab applicator, as shown and described.

DESCRIPTION

FIG. 1 is a front perspective view of a recloseable swab applicator of the present invention; FIG. 2 is an exploded perspective view thereof, showing the swab applicator of FIG. 1 in an open position; FIG. 3 is a front elevation view thereof; FIG. 4 is a rear elevation view thereof; FIG. 5 is a right elevation view thereof; FIG. 6 is a left elevation view thereof; FIG. 7 is a top plan view thereof; and, FIG. 8 is a bottom plan view thereof.

(Continued)

The broken lines shown in FIG. 2 illustrate portions of the recloseable swab applicator that form no part of the claimed design.
